ATTORNEY.

UNITED STATES PATENT OFFICE.

GEORGE A. SHIELDS, OF COLUMBUS, OHIO.

MACHINE FOR DRAWING SHEET-GLASS.

1,133,752.

Specification of Letters Patent. Patented Mar. 30, 1915.

Application filed May 28, 1913. Serial No. 770,366.

To all whom it may concern:

Be it known that I, GEORGE A. SHIELDS, a citizen of the United States, residing at Columbus, in the county of Franklin and State of Ohio, have invented certain new and useful Improvements in Machines for Drawing Sheet-Glass, of which the following is a specification.

The present invention relates to improvements in machinery for drawing sheet glass, and embodies certain novel combinations and arrangements of parts by means of which the glass may be heated to the desired plasticity; permitted to flow to a waiting receptacle or pot; and drawn from the pot in cylindrical form after which it is properly disposed of. These described features will be apparent in the following specification, and accompanying drawings in which I have illustrated one complete example and several modified forms of the physical embodiment of my invention, constructed according to the best mode I have so far devised for the practical application of the principles of the invention.

In the drawings: Figure 1 is a vertical sectional view showing the drawing machinery employed with the tank and oven. Fig. 2 is a view at the front of the furnace 30 showing the ovens and glass pots in section, and showing particularly the shiftable drawing device, and its connections. Fig. 3 is a transverse sectional view through a hinged, asbestos, cylindrical shield which encompasses the glass cylinder as it is drawn. Fig. 4 is an enlarged detail view of the drawing tube and its connections.

Referring particularly to Figs. 1 and 2 it will be noted that the furnace or tank 1 in which the glass is melted is formed with a pair of side ports 2' 2' which open into the tank from suitable flues 3.

In connection with the furnace or tank of Figs. 1, 2, I have illustrated a pair of ovens 6 and 6', and the top of each of the ovens is formed with a circular open seat 7 that is connected to the front wall of the furnace by a trough 8 which opens into the interior of the tank. Each trough is equipped with a gate 10 which extends there-across, and the gate may be lifted by means of the draw bar 11 and rocker arm 12 to regulate the flow of plastic glass through the trough.

The pair of ovens are provided with a common flue for the heat from the re-heat-

ing burners 14, which are located in the lower part of the ovens. These re-heaters are for the purpose of maintaining the heat of the plastic glass after it has flowed through the troughs and into one of the pair of glass pots 16, 16'. These pots have double receptacles for the glass and are supported on posts 17 rising from the open floor 18 of the oven, and are located directly beneath the open top of the oven in line with the opening or seat 7.

The glass pots are reversible and may be manipulated by means of a pair of tongs 19 suspended from a track 20 and provided with rollers 21 (Fig. 1) in order that the pot may be withdrawn through the opening 22 in the front of the oven.

A lifting device for the pot is illustrated in Fig. 1 and comprises a foot bar or pedal 23 that projects above the floor line and is connected to a lever 24, fulcrumed at 25 in the oven wall. This lever contacts with a lifting device 26 made up of clay legs and a top 27, the latter engaging the under side of the glass pot when lifting the pot.

The glass is drawn from the pot in cylindrical form by a single device, although I employ a plurality of glass pots and corresponding ovens. The drawing tube 28 is formed with a foot piece 29 which is adapted to contact with and attach to the plastic glass in the glass pot. The tube is supported in a cross head 30 slideable on the guide bars or rods 31 which form a suspending, shiftable frame, with braces 32, and a cylindrical shield or covering 33 preferably of asbestos. The drawing tube communicates with the passage 34 in the cross head and the air hose 35 for blowing, is attached to the cross head. The frame is formed with a pair of hinged doors or walls 36 and 37 adapted to open outwardly and expose the interior of the asbestos-lined cylinder.

The cross head 30 is suspended by a rope 38 from a drum 39, and the rope, after passing through a pair of guide rollers 40 supported in a cross bar 41 on the rods 31, may be wound upon this drum. The drawing tube and its frame are shiftable from one glass pot 16 to the other one 16', and for this purpose the machinery is supported in an upright frame 42 whose top beam 43 forms a track for the rollers or wheels 44 of a carriage 45. In Fig. 2 it will be seen that the carriage, drum 39 and the uprights 31 of the drawing frame are compactly em-

ranged to slide on a revolute shaft 46 which is revolved from a motor 47 by the sprocket wheels 48, 49 and chain 50. The carriage, drum and drawing frame are shifted by means of the ropes 51, 52 and winding drums 53, 54. The drums are turned by handles 55 and the ropes pass over idle pulleys 56 journaled on the beam 43 and are attached to the carriage at either end. The drum 39 may be provided with a key to travel in a groove in the shaft 46 so that it may be revolved at any position. A forwardly projecting bracket 57 is shown (Fig. 1) from which a pair of shears may be suspended for use in cutting the plastic glass, and a pyrometer is indicated at 58, 58, for indicating the degree of heat in the ovens.

The material in the tank or furnace is heated to the required temperature, and the glass is drawn off from the batch through one trough 8 at a time. Thus in Fig. 2 assuming that pot 16' is to be filled the gate 10 is opened to permit the molten glass to flow through the trough to the pot, and when a sufficient quantity has been deposited therein the gate is closed. The drawing tube is now lowered with the foot 29 in the molten glass, and the blowing device in operation, the drawing tube is lifted by means of the cord 38 and drum 39, which action pulls or draws a hollow cylindrical sheet up inside the asbestos shield 33. When a sufficient length has been drawn, the cylinder is cut off below the shield, the hinged doors of the shield opened and the shield and glass cylinder swung to the right (Fig. 1) so that the glass cylinder may be removed and finished in usual manner. The glass pot 16' is now reversed and the receptacle is cleaned

by heat from the burner 14. By turning crank of drum 53 the drawing mechanism is pulled over to the glass pot 16 which has been previously filled with molten glass, and the operation of drawing is repeated. Thus the drawing machine is carried back and forth, the used receptacles are cleaned, and the cylinders of glass are continuously produced without loss of time, and with slight expenditure of labor.

What I claim is:—

1. The combination in a glass drawing machine with a supporting frame and a movable carrier thereon, of a revolute shaft supported in the frame and carrier, guide bars movable on the shaft and means for moving them, a hollow cross head slideable on the bars, a blowing hose attached to the upper portion of the cross head, a drawing tube attached to the lower portion of the cross head, a drum on the shaft, and a rope wound upon the drum and connected to said cross head.

2. The combination in a glass drawing machine with a supporting frame and movable carrier thereon, of a revolute shaft supported in the frame and carrier, oscillatable and laterally movable guide bars on the shaft, a hollow cross head slideable on the bars and having a blowing hose and drawing tube, a drum on the shaft and a rope connected to the cross head, and an openable shield surrounding said drawing tube.

In testimony whereof I affix my signature in presence of two witnesses.

GEORGE A. SHIELDS.
